TABLE ATTACHMENT

Gertrude Crose Sherman, San Francisco, Calif.

Application November 27, 1933, Serial No. 699,981

3 Claims. (Cl. 248—316)

The present invention relates to improvements in table attachments, and has particular reference to an attachment for accommodating parcels, purses or similar objects.

5 It is particularly proposed to provide an attachment of this character in connection with tables used at restaurants and hotels, so as to enable a patron to place his parcels conveniently in a safe place without cluttering the top of the table.

10 More particularly it is proposed to provide an attachment of the character described that is disposed underneath the table top, in front of the person seated at the table.

15 It is further proposed to provide an attachment of the character described in the nature of a pocket into which the parcels may be inserted and which will automatically close itself so as to hide the parcels from view, unless the parcels are of 20 such size as to make the closing of the pocket impossible, in which case the pocket will remain open for the accommodation of larger parcels.

25 It is further proposed in the present invention to provide an attachment for holding parcels that will not interfere with the normal use of the table.

Further objects and advantages of my invention will appear as the specification proceeds.

The preferred form of my invention is illustrated in the accompanying drawing, in which 30 Figure 1 shows a vertical section through my attachment in its relation to the top of a table, as seen from line 1—1 of Figure 2;

35 Figure 2 a top plan view of the attachment, the table top being omitted;

Figure 3 a fragmentary front view of the attachment as seen from line 3—3 of Figure 1;

40 Figure 4 a vertical section similar to that of Figure 1, but on a reduced scale, and of a modified form;

45 Figure 5 a perspective detail view of a modified form of bracket adapted to be used in connection with my attachment.

While I have shown only the preferred form of 50 the invention, I wish to have it understood that various changes or modifications may be made within the scope of the claims hereto attached without departing from the spirit of the invention.

In its preferred form my invention comprises a 55 substantially channel-shaped pocket 1 consisting of a shelf 2, and a supporting means including a substantially semi-circular section 3 joining the rear end of the shelf as at 4, and two clips 5 projecting from the free end of the semi-circular section, the clips being bent as at 6 to present two flat sections 7 and 8, the flat sections 7 run-

ning substantially parallel to the shelf 2. The semi-circular section 3 is arranged substantially at right angles to the shelf 2 so as to form a pocket therewith as shown in the drawing.

The extremities of the clips 5 are pivoted as 5 shown at 9 to a pair of brackets 10, each including a plate 11 adapted for fastening to the under face of the table shown at 12 by means of screws 13, and a plate 14 projecting perpendicularly therefrom in a downward direction, the plate 14 having the pivot 9 projecting laterally therefrom. It will be noted that the pivot 9 is spaced from the under face of the table, and that a spring 15 is provided between the under face of the bracket and the section 8 of each clip 5 for urging the section 8 downwardly, whereby the shelf is urged into an inclined position as shown in Figure 1, with its front edge 16 bearing against the under face of the table near the margin thereof. The spring 15 is held in place by small projections 17 and 18 extending from the bracket and the section 8 respectively.

The front edge 16 of the shelf 2 may be depressed into the horizontal position shown in dotted lines in Figure 1, and in that case the 25 section 7 of each clip 5 bears against the under face of the bracket, and lies flat against the same so as to prevent further downward movement of the shelf 2, and to support the same in horizontal position. When the shelf is urged into 30 horizontal position the springs 15 yield sufficiently to allow of this movement, and when pressure is released the springs urge the shelf into the inclined position shown in full lines in Figure 1. The front edge 16 is preferably rolled and 35 provided with a central recess 16' for facilitating the operation.

The manner of using the device thus far described will be readily understood from the foregoing description. A person desiring to sit down 40 at the table, and carrying parcels, will depress the front edge 16 of the shelf 2 thereby opening the pocket, and will then insert such parcel or parcels as she may wish to accommodate. If the parcel is sufficiently large to occupy the entire 45 space available in the pocket, the latter will be forced into the horizontal position shown in dotted lines which is its position of maximum capacity. In that position the section 7 bears 50 against the bracket and prevents further downward movement of the shelf. If the parcel or parcels to be accommodated occupy only a portion of the space available, the springs 15 will urge the shelf into the inclined position and will 55 cause the same to take either the position indi-

cated in Figure 1, or any intermediate position depending upon the size of the parcels placed inside of the pocket.

While my attachment has been described in connection with the under face of a table top, it may be used in connection with any vertical surface.

Figure 4 shows a slight modification of my invention in which weights 18' are substituted for the springs 15 for urging the shelf 2 into the inclined position. Figure 5 shows a modified form of bracket made of a piece of wire so as to present an intermediate section 19, two eyes 20 at the ends thereof adapted to receive the screws 13, a pivot 21 and a small projecting stud 22 adapted to serve as one of the positioning members for the spring 15.

If a small, yet heavy, object is placed on the shelf, the shelf will be swung into full open position. The springs 15 can be arranged for counter-balancing the shelf so as to hold it in closed position when empty and to remain open when supporting any object. The pivot 21 of the bracket shown in Figure 5 is threaded at 21' for receiving a nut (not shown) for holding the clip 5 against transverse movement while still permitting the clip to rotate on the pivot.

I claim:

1. In combination with a table, brackets secured to the underside of the table, a shelf pivoted

to the brackets and having a flat parcel supporting portion, said shelf having "stop" flat portions paralleling the parcel supporting flat portion and designed to abut the undersurface of the table when the parcel supporting portion is parallel with the plane of the table, and means for yieldingly swinging the parcel supporting portion about a horizontal axis into an inclined position where the front edge thereof will abut the table.

2. A pocket attachment for a table or the like 10 and comprising a sheet of material shaped to form a bottom and a back portion, means pivotally securing the back portion to the table, and spring means for yieldingly urging the bottom upwardly into a position where the front edge thereof will 15 contact with the table, said back portion carrying stops for limiting the swinging of the bottom portion beyond a substantial horizontal position.

3. A pocket attachment for a table or the like 20 and comprising a sheet of material shaped to form a bottom and a back portion, means pivotally securing the back portion to the table, and spring means for yieldingly urging the bottom upwardly into a position where the front edge thereof will contact with the table, said back portion carrying 25 stops for limiting the swinging of the bottom portion beyond a substantially horizontal position, the sides of the attachment being open.

GERTRUDE CROSE SHERMAN. 30
